CART HANDLE HAVING A PRINTED
LEGEND THEREON

Edwin J. Buczak, Worcester, Mass., assignor to Parker Metal Goods Company, Worcester, Mass., a corporation of Massachusetts
Continuation and division of application Ser. No. 381,732, July 10, 1964. This application Dec. 22, 1967, Ser. No. 697,553

1 Claim. (Cl. 40—308)

ABSTRACT OF THE DISCLOSURE

A cart handle comprising a U-shaped frame having side arms connected by a horizontal cylindrical metal tube serving as a hand grip, a coating on said tube formed of a metal protective colored film of heat baked enamel, a printed legend in a contrasting color on said film, a transparent, injection moldable thermoplastic synthetic resin body of low heat conductivity shaped as a solid casing extending throughout the length of the hand grip and sealing and protecting said printed legend, said resin body forming a cylindrical lens much larger in diameter than that of the metal tube which forms a grip portion of a substantial size and magnifies the legend materially.

This case is a division and continuation of my prior application Ser. No. 381,732, filed July 10, 1964, and now abandoned.

This invention relates to a cart handle grip and more particularly to a grip having a printed legend which is irremovable and fully protected.

It is often desirable to provide the handle of a market cart or other type of vehicle with a legend or other designation, such as the name of the store owner of the cart, as insurance against theft or other loss. Various attempts have been made to mark such a cart handle, such as by gluing a printed label on the inside of a half sleeve and riveting the latter to a second half sleeve on the handle, but the rivets are objectionable and the marking is not fully protected from the weather. Also, a legend has been applied by printing a trade name on a plastic sleeve which is mounted on the handle and covered by a second sleeve slidably forced thereover. Moisture can enter between the sleeves and discolor the printing. Also, this requires a large inventory of sleeves and that the sleeves be axially straight or be made of a soft or flexible material which lacks durability or resistance to impact and cannot protect the legend adequately.

The primary object of this invention is to overcome the disadvantages inherent in such attempts and to provide a cart which has a handle grip of low heat conductivity which is marked with a legend, such as the owner's name, that is legible, permanent and fully protected from the weather elements and which cannot be removed or altered. Other objects will be apparent in the following disclosure.

In accordance with my invention, I provide a cart handle having a desired legend imprinted thereon which is sealed permanently within a transparent cover insuring that the legend will always be visible and protected from the elements of the weather, such as rain or freezing conditions, and which provides a handle grip of low heat conductivity and of high resistance to impact or other destructive forces.

Referring to the drawings showing the preferred structure and the sequence of steps and an associated molding structure for making the same:

FIG. 1 is a fragmentary perspective view of the grip portion of a metal tube which forms a cart handle;

2

FIG. 2 is a similar view showing the application of masks and spray painting the grip portion of the handle;

FIG. 3 is a similar view showing a suitable legend stencilled on the painted portion;

5 FIG. 4 is a similar view showing the grip portion of the handle formed by an injection molded cover irre- movably mounted over and encasing the legend;

FIG. 5 is fragmentary perspective view of a completed handle comprising the grip of FIG. 4;

10 FIG. 6 is an enlarged sectional view taken on the line 6—6 of FIG. 4; and

FIG. 7 is a diagrammatic showing of part of a conventional injection molding machine suitable for forming the molded cover which forms the grip portion of the handle.

15 This invention is particularly applicable to a nesting market cart shown in my prior Patent 3,112,934 of Dec. 3, 1963, as well as other market carts or hand propelled vehicles such as a baby carriage or the like, herein classified as carts. The handle may be shaped as shown in my

20 prior patent, which comprises a tubular metal portion forming a hand grip and arms attaching the grip portion to the undercarriage and it may be a single one-piece structure, as shown particularly in FIG. 5, or the grip portion may be separate from the arms. The handle grip

25 structure is preferably made of tubular steel 10 (FIG. 1) which commonly has a diameter of about $\frac{3}{4}$ of an inch and it may be chromium plated. The grip portion of the handle is preferably straight for the convenience of the person who pushes the cart. It is desirable to apply to 30 the handle a legend, such as the trade name of the store owner or a desired pictorial design suitable for other purposes, which is arranged on the grip portion of the handle or on one of the arms.

To provide this legend, I preferably coat the grip por- 35 tion of the handle as shown in FIG. 2 with a suitable pigment carrier, such as an enamel or lacquer of desired color, indicated as red in the figure. This coating 12 may be a suitable enamel or lacquer capable of being

40 baked to a hard condition and of adhering and protecting the metal and forming a continuous smooth surface on which the legend or design may be applied. The coating may be applied by a suitable spraying apparatus. To this end, I may provide masks 14 which protect the tube 10 from the spray outside of the area to be spray painted.

45 Then, the enamel or lacquer is sprayed onto the handle between the masked portions to form a film coating. The handle is coated around its entire circumference for an artistic effect. Thereafter, the coating is baked on the handle in accordance with standard procedure, such as 50 by subjecting the grip portion of the handle to a temperature of 350° F. to harden the enamel. Various standard procedures and materials may be employed to provide this colored coating of a material which is suitable for the application of the printed legend.

55 The next step is to apply a legend, such as a name or design, to this paint coating. Of the various methods which may be adopted, I prefer to print the legend 16 (FIG. 3) on that coating by means of a paint, such as an ink of a suitable contrasting color, shown in the figure as being of a gold color. The preferred procedure is that of employing a silk screen in accord with the standard practice which has a porous portion showing the legend surrounded by an impervious portion. A suit- 60 able paint is forced through the porous portion onto the painted handle grip, thus imprinting the legend on the handle. The paint or ink may be baked on the handle to a hardened condition.

The procedure as above-defined has provided a legend 65 on a coated portion of the handle grip which is in a contrasting color relative to the coating 12. The next step, illustrated diagrammatically in FIG. 4, involves the

70

application of a transparent body 18 to this central printed portion of the handle. It is necessary that this body be formed of a transparent material which will adhere firmly to the handle and be irremovable and capable of resisting impact blow as well as being impervious to moisture and unaffected materially by winter temperatures and which is such a poor conductor of heat that it will form a grip portion capable of protecting the hands of the user. This material is preferably a suitable synthetic moldable plastic molded permanently in position as by an injection molding apparatus. A satisfactory material for this purpose and which has the desired characteristic is "Tenite" cellulose acetate butyrate manufactured by Eastman Chemical Products, Inc. This material as supplied is capable of being softened and molded in a standard or a suitable injection molding machine.

A conventional machine, as is understood, comprises a stationary platen 20 and a movable platen 22 suitably mounted and arranged as shown in FIG. 7 so that the grip portion of the handle 10 may be inserted in the half mold cavity in the platen 20, after which the half mold in the movable platen 22 is closed and locked. This may be done by means of a suitable locking mechanism shown in the figure as a toggle joint 24 arranged to be operated by hydraulic mechanism 26 in such a manner as to bring the movable mold platen 22 into position where the grip portion of the handle is fully enclosed and positioned for the application of the molding compound. The latter is supplied from the hopper 28 to the mold cavity 30 in the machine where it is forced by the hydraulically driven ram 32 through a sprue 34 into the cavity provided by the two mold halves. The butyrate flows evenly around the handle tube 10 and its printed coating, and thus is molded in position. The molds are so shaped as to provide the beveled ends 36 of the molded body (FIG. 4) and various precautions are taken as are well understood in the industry to insure a proper molding operation. The apparatus, which is no part of this invention, comprises a stationary wall 38 secured by tie rods 40 to the stationary platen 20 and so arranged that the toggle may provide the required mold locking operation. The machine is so arranged that the curved cart handle of FIG. 5 may be properly mounted in place with the grip portion of the handle located in the molding chamber. Various other types of injection molding apparatus may be employed for the operation in making this outer sleeve or covering body 18.

The butyrate forms a transparent body 18, and that body is given considerable thickness as shown, so that the grip portion of the handle has a materially larger diameter than has the tube 10. The butyrate is a substance of low heat conductivity and thus in the winter time it provides a safe and comfortable grip for the bare hands of the cart user. The butyrate makes a thorough contact with the coated and printed handle and it is impervious to water and so cannot permit moisture to contact the printed legend. This material does not freeze or crack and it thoroughly protects the printed portion from all weather conditions. The injection molding is accomplished under high pressure as is understood, and this serves to seal in the printed portion permanently and prevent any discoloration or other detrimental effect on the legend. Owing to the characteristics of the cellulose acetate butyrate, the cart handle will resist high impact

or other blows and is sufficiently durable to outwear other parts of the cart.

One advantage of the thick body 18 is indicated in FIG. 6, showing in cross section how the legend is optically enlarged to the eye of the observer by the cylindrical lens effect of the body 18. That is, the legend of the size indicated in FIG. 3 appears to have the much larger size shown in FIG. 4. This will be readily apparent by inspection of FIG. 6, where the legend 16 subtending the angle indicated by the dotted radial lines 40, appears to have a much larger size as indicated by the arc portion 42 of that figure. Thus, the comparatively small-sized printing of FIG. 3 appears to be enlarged materially as indicated diagrammatically in FIG. 4, and yet the legend, because of the extreme transparency of the body 18 is clear and easily observed.

By the above-described procedure, I have provided a cart handle grip with a printed legend thereon, which is enclosed by and sealed permanently in a transparent body molded on the handle. The handle is preferably formed of a metal tube and its coating provides a color contrast for the legend. I preferably encase the grip or other portion of the tube in a film of a desired color which is capable of contrasting materially with the pigment of the printed legend. After the legend has been printed on the film, a transparent body is cast or injection molded over the legend and thus protects and seals the latter completely from weather conditions. This body is preferably a synthetic thermoplastic or thermosettable resin, and preferably one of the general type of cellulose acetate butyrate, which is highly transparent and has such a low heat conductivity that it provides a satisfactory grip portion for the comfort of the cart user. Other features and advantages will be readily apparent.

Various modifications of this article may be employed, and it is to be understood that the above disclosure is to be interpreted as setting forth my preferred structure and not as imposing limitations on the appended claim.

I claim:

1. A cart handle comprising a unitary substantially tubular frame having side arms connected by a horizontal cylindrical hand grip shaped for manual propulsion of the cart, said hand grip being a straight metal tube, a coating on said tube formed of a metal protective colored film of heat baked enamel, a printed legend in a contrasting color on said film, a transparent injection moldable thermoplastic synthetic resin body of low heat conductivity shaped as a solid cylindrical casing extending throughout the length and circumference of the hand grip, said resin body having its ends sealed and protecting said printed legend from external contacts and weather conditions, said resin body forming a cylindrical lens much larger in diameter than that of the metal tube which provides a grip portion of a substantial size and magnifies the legend materially.
